UNITED STATES PATENT OFFICE.

OSCAR A. YOUNGREN, OF SHERIDAN, WYOMING.

SPRING-SEAT.

1,189,769.

Specification of Letters Patent.

Patented July 4, 1916.

Application filed July 5, 1913. Serial No. 777,561.

To all whom it may concern:

Be it known that I, OSCAR A. YOUNGREN, a citizen of the United States, residing at Sheridan, Sheridan county, and State of Wyoming, have invented and discovered certain new and useful Improvements in Spring-Seats, of which the following is a specification.

My said invention consists in an improved construction and arrangement of parts of spring seats especially designed for the use of engineers and firemen in cabs and locomotives, but also adapted for use in many other places, whereby such a seat is provided which is supported from the wall of the cab, or any side support, and occupies a minimum of space and may be easily and quickly put into place and supported in operative position or dropped out of the way as desired, all as will be hereinafter more fully described and claimed.

Referring to the accompanying drawings, which are made a part hereof, and on which similar reference characters indicate similar parts,

Figure 1 is a side elevation of a seat of the character described, embodying my said invention, Fig. 2 a view as seen when looking in the direction indicated by the arrows from the dotted line 2—2 in Fig. 1, and Fig. 3 a detail section on the dotted line 3—3 in Fig. 2.

In said drawings the portions marked A represent a supporting or base plate, B the main supporting bracket or bar for the seat, C a housing for the springs, D the seat and E a distance rod or brace. The base plate A is of appropriate form and preferably of metal and adapted to be secured by bolts or screws to the side wall of the cab, or any other side support provided. Near its lower end it is provided with forwardly projecting arms 10, and with a centrally disposed eye 11, and near its upper end it is provided with a hook-shaped coupling member 12.

The arm B is of the form best shown in Fig. 1, having at its rear end an upwardly projecting arm having a hook-shaped coupling member 13 adapted to engage with the hook-shaped coupling member 12 on the base plate A. Adjacent to the angle between the main portion of said bar B and the upwardly extending rear end are downwardly extending arms 14 which fit within the sides of the housing C. Said arm B ex-

tends outwardly a distance desired for the purpose and supports the seat on its outer end, as will be presently described.

The housing C is composed of slotted sides and end cast as a single piece or of any other appropriate form to support the spring mechanism and is supported at its rear end between the arms 10 of the base plate A by means of pivot bolts 15 extending through diagonal slots 16 in said arms into perforations in said housing. The upper side of said housing supports the arm B which rests and is adapted to have a sliding movement thereon. Said housing C is formed with long slots 17 in its opposite sides near its rear end and with like slots 18 in its opposite sides near its forward end. A cross-bar 19 is mounted to slide in the slots 17 and a similar cross-bar 20 is mounted to slide in the slots 18. Said cross-bars 19 and 20 are connected to each other by a series of stiff coiled springs 21, 22, 23, and 24, the opposite ends of said springs being connected to said oppositely disposed bars. The lower ends of arms 14 of the bar B are formed with apertures through which the cross-bar 19 extends forming a loose connection. Bolts 25 with hook-shaped rear ends 26 are hooked around the cross-bar 20 and project through the front end of casing C where they are provided with nuts 26^a by which means said bar 20 may be adjusted to regulate the tension of the springs connected therewith.

The seat bar D is angular having a cushion d mounted on the upper side of its horizontal arm and at its angle is connected by a pivot rod 27 to the outer end of the bar B. Its vertical arm extends downwardly for a distance below the outer end of said bar B and is connected by a pivot 28 to the outer end of the distance rod E. Said distance rod E extends rearwardly and at its rear end is connected by a pivot-bolt 29 with the eye 11 on the lower end of base plate A.

In operation the parts being in the position shown by whole lines in Fig. 1, and the weight of the person being added thereto, the seat will be depressed as indicated by dotted lines in the same figure, but the distance rod E coöperating with the supporting bar B will serve to maintain the seat D in a horizontal position at all elevations. When it is desired to drop the seat out of use the front end may be raised when the bolts 15

will slide forward in the slots 16 in the arms 10 and uncouple the parts 12 and 13 when the entire structure may be dropped downward in a vertical position turning on the 5 pivots 15, and the seat D will be held in its normal relative position to the other parts by means of the distance rod E and the bar B. Whenever it is desired to use the seat it is only necessary to lift it up into horizontal 10 position, catch the hook part 18 over the hook part 12 and it is immediately ready for use. By adjusting the bolts 25 the tension of the springs may be regulated to adapt the seat for the weight of any user 15 so as to insure the most comfortable and desirable results.

Having thus fully described my said invention what I claim as new, and desire to secure by Letters Patent is:

20 1. A spring seat comprising a supporting plate, a housing pivoted to said supporting plate, a seat supporting bar slidingly connected with said housing and provided with a connection by which it may be coupled to 25 and turn on said supporting plate at a point removed from the pivot of the housing, springs connected at one end to said seat supporting bar and at the other end to said housing for supporting said bar yieldingly, 30 and a seat supported on said bar, substantially as set forth.

2. A spring seat comprising a base having a support, a housing pivoted to said base at a point rearward from said support, a 35 bar slidably mounted on said housing and provided with a part extending in one direction and formed to engage and turn on the support on said base and with arms extending in the opposite direction, springs connected at one end to said arms and at the 40 other end to said housing, and a seat mounted on the outer end of said bar, substantially as set forth.

3. A spring seat comprising a base having a support, a housing pivotally mounted 45 on said base at a point removed from said support to have a limited sliding movement, a seat supporting bar mounted on said housing to have a sliding movement, one end of 50 said seat supporting bar being adapted for connection with the support on said base, a seat mounted on the outer end of said seat supporting bar, springs connected with said seat supporting bar at one end and with 55 said housing at the other end, and means connected with the base and the seat supporting bar for maintaining said seat in a horizontal position when in use, substantially as set forth.

60 4. A spring seat comprising a supporting base, a housing supported to pivot and slide in relation to said base, a seat supporting bar mounted on said housing and formed

with a part adapted to be detachably secured to said base to turn thereon and with arms 65 extending within said housing, a cross-bar extending through slots in the sides of said housing and also connected with said arms, another cross-bar mounted in slots in the opposite end of said housing, springs connecting said cross-bars, bolts adjustably connecting the other cross-bar with the housing, and a seat appropriately mounted on the seat supporting bar, substantially as set forth. 75

5. A spring seat comprising a base support, a housing pivotally carried thereby, a bar slidingly mounted on said housing and adapted to be detachably secured to said base to turn thereon, springs connected at 80 one end to said bar and at the other end to said housing, a seat pivoted on the outer end of said bar, an arm depending from said seat to below its pivot, and a distance rod connecting the lower end of said depending arm to the base, whereby said seat may be maintained in normal relation with the other parts regardless of their position, substantially as set forth.

6. A spring seat comprising a base support having forwardly projecting arms, a housing pivoted thereto on pivots mounted in inclined slots in said arms, a seat supporting bar detachably secured to said base plate to turn thereon, springs connected to 95 said housing and to said seat supporting bar, a seat pivoted to the outer end of said seat supporting bar and formed with a depending arm, and a distance rod connecting the lower end of said depending arm with 100 said base plate whereby said seat may be dropped upon its pivot and the parts maintained in normal relative position with each other, substantially as set forth.

7. A spring seat comprising a base support, a seat bar slidably mounted on means for attaching to said base support, said attaching means pivotally connected with said base support, a second means for pivotally attaching said seat bar to said base support, 110 springs interposed between the seat bar and the means for attaching it to the base support, a seat pivoted on said seat bar, and means connected with said seat bar and base support for maintaining said seat in normal 115 relation to the other parts, substantially as set forth.

In witness whereof, I have hereunto set my hand and seal at Sheridan, Wyoming, this 30th day of June, A. D. nineteen hundred and thirteen.

OSCAR A. YOUNGREN. [L. s.]
